UNITED STATES PATENT OFFICE

156,803

CREAM PITCHER

Jack Badash, Brooklyn, N. Y.

Application June 19, 1948, Serial No. 147,092

Term of patent 3½ years

(Cl. D44—21)

To all whom it may concern:

Be it known that I, Jack Badash, a citizen of the United States of America, residing in Brooklyn, county of Kings, and State of New York, have invented a new, original, and ornamental Design for a Cream Pitcher, of which the following is a specification, reference being had to the accompanying drawing, forming part thereof.

Fig. 1 is a front perspective view of a cream pitcher showing my new design.

Fig. 2 is a rear perspective view thereof.

I claim:

The ornamental design for a cream pitcher, substantially as shown.

JACK BADASH.
